Patented Aug. 24, 1920.

Inventor

Monroe E. Heilbrun
By his Attorney,
Hans Wittenhofer

UNITED STATES PATENT OFFICE.

MONROE E. HEILBRUN, OF NEW YORK, N. Y.

DESIGN FOR AN EMBLEM, BADGE, BUTTON, OR SIMILAR ARTICLE.

56,155.

Specification for Design.

Patented Aug. 24, 1920.

Application filed December 24, 1918. Serial No. 268,175. Term of patent 3½ years.

To all whom it may concern:

Be it known that I, MONROE E. HEILBRUN, a citizen of the United States, residing at the city, county, and State of New York, have invented a new, original, and ornamental Design for Emblems, Badges, Buttons, and Similar Articles, of which the following is a specification, reference being had to the accompanying drawing, forming part thereof.

The figure is a plan view of an emblem showing my new design.

I claim:

The ornamental design for an emblem, badge, button, or similar article substantially as shown.

MONROE E. HEILBRUN.
